ABSTRACT OF THE DISCLOSURE

A process for producing radioactive indium-113^m by eluting from neutron irradiated tin that is retained on a 15

This invention relates to a novel process for the production of radioactive indium-113^m. In one aspect, this invention relates to a novel process for the production of radioactive indium-113^m in high yields. A further aspect of this invention is directed to a novel process for the production of radioactive indium-113 which can be obtained in a high degree of purity.

Recent medical investigation has shown that indium-113^m is an extremely useful tool for diagnosis. High purity indium-113^m is used primarily as a radioisotope in a variety of medical research and diagnosis. It is well suited for liver, lung, blood pool and tumor scanning, and is preferred over other radioactive isotopes because of its short half-life which results in reduced exposure of the organs to radiation. In addition to medical uses, indium-113^m can also be employed in industrial applications, such as in the measurement of flow rates, process control, radiometric chemistry, and the like. Since the radioisotope sought to be used has such a short half-life, it is common practice to ship the users of the isotope the parent element; in this case neutron irradiated tin. The user then extracts the indium-113^m from the tin as his needs require. The production of indium-113^m and its decay is illustrated as follows:

where ¹¹³Sn is obtained by neutron irradiation of ¹¹²Sn; ¹¹³Sn decays by the electron capture process to ^{113m}In with the half-life of 118 days; ^{113m}In, a metastable isotope, decays to the ground state, ¹¹³In, by the isomeric transition process with the half-life of 104 minutes.

In the past, radioactive indium-113^m has been produced by a variety of methods. For example, I. Stonski and V. N. Pybakov (Chemia Analityczna, 4, 877, 1959) prepared an indium-113^m generator using an anion exchange resin. The indium-113^m was eluted with 3 molar hydrochloric acid. The radiochemical purity of indium-113^m was approximately 99 percent. The indium-113^m solution thus obtained was not suitable for medical formulation because of the strong acid strength, the significant tin-113 breakthrough and the possible contamination by the radiation degradation products of the organic resin. Another type of generator developed in the Oak Ridge National Laboratory used hydrous zirconium oxide as the adsorber of tin-113 from which indium-113^m was eluted with methyl ethyl ketone.

However, to date, none of the work reported in literature has been entirely successful in the development of an indium-113^m generator which meets present day medical requirements. It is therefore an object of this invention to provide a more efficient method for producing radioactive indium-113^m. Another object of this invention is to provide a process for preparing radioactive indium in a high

2

degree of purity and by an extremely reproducible process. A further object of this invention is to provide a process which avoids the need for separating radioactive products and other impurities. These and other objects will readily become apparent to those skilled in the art in the light of the teachings herein set forth.

It has now been discovered that the aforementioned objects can be achieved by a process which comprises the steps of (a) irradiating a tin compound, (b) dissolving the tin compound, (c) diluting the dissolved tin compound with water, (d) contacting the diluted tin solution with silica gel, (e) selectively extracting indium-113^m from the silica gel substrate with dilute acid.

Operating in the aforesaid manner provides a selective separation of indium-113^m from all other elements in the dissolved tin compound with very high efficiency, i.e., over 90 percent. In addition the process of this invention is readily reproducible and simple to operate.

Although a variety of tin compounds are suitable for use in the process of this invention the preferred tin target is thin metal. Particularly preferred is tin metal enriched in the stable tin-112 isotope. In the event that tin compounds other than tin metal are employed, it is preferred to isolate the tin component after irradiation. Illustrative tin compounds which can be employed as the source of tin include, among others, tin metal, tin oxide, tin nitrate, tin sulfate, organic tin compounds such as tetraphenyl tin, and the like.

Irradiation of the tin compound by neutrons is a well known technique and can be effected by placing the tin compound in the irradiation zone of a nuclear reactor, neutron generator, or neutron isotopic source.

Thereafter, the irradiated tin compound is dissolved in a suitable solvent. In the case of tin metal, concentrated hydrochloric acid is employed. For other tin compounds it may be necessary to employ a basic solvent such as sodium hydroxide and perform additional reactions to isolate the tin.

It has been found to be advantageous to dissolve the tin metal in hydrochloric acid in the presence of an oxidizing agent to aid in the dissolution and to insure that the tin is in the stannic (+4) oxidation state. Hydrogen is preferred inasmuch as it is easily removed from the tin solution by heating. Other oxidants such as bromine water, permanganate, and the like, can be used but are less preferred.

Thereafter the dissolved tin compound is diluted with water in the presence of a drop or two of bromine water to insure the proper oxidation state (+4) of the tin. The solution is adjusted to provide a tin concentration in 0.3 to 0.5 molar HCl of at least about 0.5 milligram of tin, as the element, per milliliter of solution.

Silica gel is then immediately contacted with the dilute acid solution containing the tin. The preferred mesh is from 20 to 200. The silica gel can be added to a vessel containing the tin solution until thoroughly wet and then heated to enhance the deposition of the tin on the gel. Preferably the solution is heated to about 40° to 100° C. and more preferably 80° C. from 15 to 20 minutes followed by digestion at room temperatures for not less than about two hours.

Alternatively, the solution can be left at room temperature for a long period of time. However, the amount of tin deposited has been shown not to be reproducible, and may take as long as several weeks.

The silica gel containing the tin is then transferred to an appropriate elution system such as a column, preferably glass, or other inert material. The supernatant liquid is allowed to drain and the substrate washed with approximately 10 to 200 milliliters of 0.01 to 0.1 molar HCl, more preferably 0.07 molar HCl.

The loaded column which contained $113m_{\text{Sn}}$ - $113m_{\text{In}}$ activity can subsequently be eluted or milked repeatedly for $113m_{\text{In}}$ as it is formed with an acidic solution. Preferably, it has been observed that best results are obtained when the column is eluted with 4 to 20 milliliter portions of 0.03 to 0.1 molar HCl solution. This is done by passing the desired volume of HCl through the column and collecting the effluent.

Numerous variations of the preferred embodiment described above may be practiced, as will be apparent to those skilled in the art, without departing from the basic concepts of the present invention.

As previously indicated, the process of the present invention provides a simple, method for the preparation of indium-113m in a high degree of efficiency. By this process recovery of indium-113m can be effected with hydrochloric acid in efficiencies of 90% and higher, over a pH range of about 0.5 to about 1.7 without appreciable dissolution of the silica gel or removal of any tin from the silica gel substrate.

A further advantage characteristic of the process of this invention, is that the substrate and/or the entire elution system can be sterilized, i.e., by autoclaving at the normally prescribed temperatures and pressures.

In contrast, the previously known hydrous zirconium oxide, which can also be loaded by the above-described procedure, has elution efficiencies greater than 50 percent and normally less than 75 percent when eluted with hydrochloric acid over a pH range of about 1.4 to about 1.6. A lower pH than 1.4 would result in appreciable dissolution of the zirconium oxide, while a higher pH results in decreased efficiencies. Under optimum elution conditions of both substrates, the major advantages of the present process are (a) higher efficiency of recovery of indium-113m from the substrate, (b) greater operating pH range over which efficient elution can be effected, and (c) sterilization of the substrate by normal autoclaving methods, i.e., steam and pressure, only slightly reduces the recoverable indium-113m, for example about 5 percent for the silica gel substrate as compared to about 20 to about 30 percent for the zirconium oxide substrate.

The following example is illustrative:

Example I

Tin metal (500 milligram) enriched in tin 112 is encapsulated in high purity quartz tubing which is then in turn secondarily encapsulated in aluminum tubing. The container is then placed in a nuclear reactor neutron irradiation zone of a high thermal neutron flux. The capsule was irradiated for approximately 500 to 5000 hours. The container is removed from the radiation zone to an appropriate shielded facility. The tin is removed from its encapsulation material, dissolved in concentrated HCl which contains several drops of hydrogen peroxide (30 percent) thereafter, the concentration was adjusted to 10 milligrams of tin per 1 milliliter of 4 molar HCl. Prior to loading, the above solution was diluted 10:1 with water containing a few drops of bromine water. Approximately 20 milligrams of tin (20 milliliters of the diluted solution) is loaded on 5 milliliters wet volume of silica gel (approximately 4 grams) by contacting the silica gel with the solution for 15 to 20 minutes at 80° C. followed by 2 to 24 hours at room temperature. The silica gel solution is then loaded to a glass column 1 x 5 centimeters which is shielded with an appropriate lead container. The supernate is permitted to drain and the silica gel washed with 125 milliliters of 0.07 molar HCl. After an appropriate time period to permit the decay of the retained tin-113 to indium-113m the available indium-113m on the column is removed by the addition of 5 milliliters of 0.07 molar HCl.

Radiometric analysis of the eluted indium-113m indicates that it contains 95 percent of the available indium-113m and the radionuclidic purity is greater than 99.98 percent. The total metal element impurity is less than 1 part per million as determined by emission spectroscopy techniques.

The substrate and/or the entire elution system can be sterilized by acceptable autoclave techniques with no reduction in radionuclidic impurity, no increase in the metal element impurities and only a slight reduction in the amount of indium-113m recoverable.

Although the invention has been illustrated by the preceding example, it is not to be construed as being limited to the materials employed therein, but rather, the invention encompasses the generic area as hereinbefore disclosed. Various modifications and embodiments of this invention can be made without departing from the spirit and scope thereof.

What is claimed is:

- 20 1. A process for producing radioactive indium-113m which comprises the steps of:
  - (a) irradiating a tin containing material in a neutron flux until the desired amount of tin-113 is formed;
  - (b) dissolving the irradiated tin containing material containing the radioactive tin-113, to obtain a tin solution;
  - (c) diluting the tin solution with water;
  - (d) contacting silica gel with said dilute tin solution, heating to a temperature of from about 40° to about 100° C., thereby loading the tin on said silica gel to provide an elution system, and
  - (e) selectively extracting said elution system with a solution consisting essentially of a dilute inorganic acid at a pH range of from about 0.5 to about 1.7 to separate indium-113 from its radioactive parent tin-113 that is deposited on the silica gel.
- 25 2. The process of claim 1 wherein said tin containing material is tin metal.
- 30 3. The process of claim 1 wherein said tin containing material is tin metal enriched in the stable tin-112 isotope.
- 35 4. The process of claim 1 wherein said irradiated tin containing material is dissolved in concentrated hydrochloric acid in the presence of an oxidizing agent.
- 40 5. The process of claim 1 wherein said tin solution is diluted to a minimum tin concentration of at least 0.5 milligram per milliliter of 0.3 to 0.5 molar hydrochloric acid.
- 45 6. The process of claim 1 wherein said diluted tin solution is contacted with said silica gel and heated at a temperature of from about 40° to 100° C., and then allowed to stand at room temperature.
- 50 7. The process of claim 1 wherein indium-113m is selectively extracted with hydrochloric acid of a concentration of from about 0.01 to 0.1 molar.
- 55 8. The process of claim 1 wherein said elution system is sterilized.
- 60 9. The process of claim 8 wherein said sterile elution system is extracted with sterile hydrochloric acid to provide a sterile solution containing irradiated indium-113m.
